EDMUND P. KINNE, OF ALLIANCE, OHIO, ASSIGNOR TO AMERICAN STEEL FOUNDRIES,
OF NEW YORK, N. Y., A CORPORATION OF NEW JERSEY.

ANTICREEP FOR WEDGE-LOCKS.

1,108,374.

Specification of Letters Patent.

Patented Aug. 25, 1914.

Application filed March 17, 1913. Serial No. 754,693.

To all whom it may concern:

Be it known that I, EDMUND P. KINNE, a citizen of the United States, residing at Alliance, in the county of Stark and State of Ohio, have invented certain new and useful Improvements in Anticreeps for Wedge- Locks, of which the following is a specification.

My invention relates to car couplers and has particular reference to a novel anti-creeping provision or lock to the lock.

My invention is particularly applicable to wedge locks; that is, locks which are adapted because of their construction to compensate for wear in the locking faces of the knuckle and lock or in the contacting surfaces of the knuckle and its pivot pin.

A wedge lock construction is being favored by many as the best means for maintaining the proper and normal contour of the coupler, it having been found in practice that many partially worn couplers are discarded for the reason that the knuckle assumes a position under draft which is outside of the permissible lines as established by the Master Car Builders' Association. However, it has also been found in practice that while theoretically a wedge lock will accomplish this result, in actual practice the lock will creep upwardly to the extent allowed by the anti-creeping provision and this anti-creeping provision being constructed to prevent creeping of the lock when in its normal unworn condition, it will permit the upward creeping of the lock to the position it will assume when the lock was new and unworn. The creeping therefore will offset the advantage secured by the wedge lock in that the anti-creeping provision is not progressively operative at all points or locking positions of the lock.

An object therefore of my invention is to provide an anti-creep or lock to the lock which shall be operative at all points or locking positions of the lock thus preventing creeping irrespective of the condition of wear of the lock or related parts.

My invention will be more readily understood by reference to the accompanying drawings, wherein,

Figure 1 is a transverse longitudinal section through a coupler having a wedge lock to which my novel anti-creeping device is applied; Fig. 2 is a transverse vertical section showing the lock in normal locking position

before wear has permitted the lock to assume a lower position, and, Fig. 3 is a similar view showing the lock in a lower position such as it will assume after considerable wear has occurred.

60

Referring more particularly to the drawings, it will be seen that I provide a coupler head 10, within which a knuckle 11 is pivoted. This knuckle is provided with a tail 12, having a locking face 13. Within the coupler head I provide guides 14, 15, located at an angle to the vertical, between which a lock 16 is guided. These guides tend to direct the lock toward the locking face 13 of the knuckle tail and as wear occurs the lock is permitted to further descend. At a point on the wall of the coupler head against which the lock abuts, I provide a recess 17, which may be narrow, as shown in Fig. 1, thus reducing the locking surface immaterially. Cooperating with the recess 17 is an anti-creeping trigger or latch 18, having a curved outer edge which cooperates with the arcuate inner wall of the recess. It will be noted that the curves of the inner wall of the recess and the outer edge of the trigger 18 are eccentric to each other and that as the lock descends the trigger assumes a new relation to the curved wall of the recess in order that a wedging action is secured between the trigger and the coupler wall. Thus even the slightest creeping action is obviated. The trigger 18 is pivoted at 19 to the locking block and projects through a slot therein, as best shown in Fig. 1. The trigger is adapted to be actuated by connection to the lock lifter 20, the upper end of which projects through an opening in the top wall of the coupler. In the lifted or released position as shown in dotted lines in Fig. 2, the anti-creeping member forms the lifting means for the lock.

75

It is obvious that the anti-creeping member may take many forms other than that shown in the drawing, it being a requisite, however, that the anti-creeping action shall follow the descent of the lock and be effective at all positions thereof.

80

I claim:

1. In a car coupler, the combination of a head having a curved anti-creeping surface, a swinging knuckle and a wedging locking block, a movable anticreeping member on said lock, said member progressively co-acting with said curved surface on the coupler 105

head in a plurality of positions of said lock to prevent creeping thereof, substantially as described.

2. In a car coupler, the combination of a head having a curved anti-creeping surface, a swinging knuckle and a wedging locking block, a swinging anti-creeping member associated with said lock, said member progressively engaging at different points on the curved anti-creeping surface in said head in a plurality of positions of said lock whereby creeping of the lock is prevented, substantially as described.

3. In a car coupler, the combination of a head, a swinging knuckle and a wedging lock, an anti-creeping latch pivoted to said lock, said latch cooperating with a curved surface on said head, the curve of said surface being eccentric to the center of rotation of said latch, and means for swinging said latch prior to lifting said lock, substantially as described.

EDMUND P. KINNE.
